UNITED STATES PATENT OFFICE.

MAURICE SCOOLER, OF NEW ORLEANS, LOUISIANA.

DESIGN FOR A HANDLE FOR SPOONS, &c.

SPECIFICATION forming part of Design No. 20,698, dated April 28, 1891.

Application filed March 11, 1891. Serial No. 384,656. Term of patent 7 years.

To all whom it may concern:

Be it known that I, MAURICE SCOOLER, of New Orleans, in the parish of Orleans and State of Louisiana, have invented a new and original Design for the Handles of Spoons, Forks, Knives, &c., of which the following is a full, clear, and exact description.

The design consists in the several figures, including the representation of a pelican feeding her young, the representation of a bale of cotton, and the representation of rice and sugar-cane stalks.

Thus *a* indicates the representation of a pelican, the same appearing in connection with the figure *b*, representing a nest containing the young birds. The nest is represented in

connection with and above a figure *c*, representing a bale of cotton.

The letter *d* indicates a figure representing a series of sugar-cane, at each end of which appear the figures *e e'*, representing, respectively, leaves and growing rice.

The several figures appear in longitudinal alignment.

I claim—

The design for the handles of spoons, forks, knives, &c., herein shown and described.

M. SCOOLER.
